(57) **CLAIM**

The ornamental design for a motor vehicle, toy replica and/or other replicas, as shown and described.

DESCRIPTION

FIG. 1 is a front and left side perspective view of the motor vehicle, toy replica and/or other replicas showing our new design;

FIG. 2 is a left side elevational view of FIG. 1;

FIG. 3 is a right side elevational view of FIG. 1;

FIG. 4 is a top plan view of FIG. 1;

FIG. 5 is a rear elevational view of FIG. 1; and,

FIG. 6 is a front elevational view of FIG. 1.

The uniform broken lines shown in the drawings illustrate portions of the motor vehicle, toy replica and/or other replicas that form no part of the claimed design. The dash-dot broken lines illustrate boundaries between claimed and unclaimed surfaces and form no part of the claimed design.
